[57] CLAIM

The ornamental design for a drive and control unit for a hydraulic tool, as shown and described.

DESCRIPTION

FIG. 1 is a perspective view of a drive and control unit for a hydraulic tool showing our new design;

FIG. 2 is a bottom plan view thereof;

FIG. 3 is a left side elevation thereof;

FIG. 4 is a rear end elevation thereof;

FIG. 5 is a top plan view thereof;

FIG. 6 is a front end elevation thereof; and,

FIG. 7 is a right side elevation thereof.
